UNITED STATES PATENT OFFICE.

ROBERT SUCZEK, OF PHILADELPHIA, PENNSYLVANIA, ASSIGNEE TO C. H. WHEELER
MANUFACTURING COMPANY, OF PHILADELPHIA, PENNSYLVANIA, A CORPORA-
TION OF PENNSYLVANIA.

FLUID-COMPRESSING APPARATUS.

Application filed May 8, 1920. Serial No. 379,712.

To all whom it may concern:

Be it known that I, ROBERT SUCZEK, a citizen of the Czechoslovak Republic, residing in the city and county of Philadelphia, State of Pennsylvania, have invented certain new and useful Improvements in Fluid-Compressing Apparatus, of which the following is a specification.

My invention relates to apparatus for compressing fluid in a plurality of stages by action thereon by ejector apparatus, in one stage employing condensable motive fluid, as steam, the condensable fluid discharged by the first stage ejector apparatus being condensed and the remaining uncondensed fluid, as air, being acted upon in a later stage by any suitable pump, as an ejector.

My invention resides in apparatus of the character referred to wherein the interstage condensing apparatus is of a structure making possible the utilization of independent streams of cooling medium, as water, and more particularly, making possible utilization of streams of cooling medium from different sources, as from the cooling system of a main condenser and from the condensate therefrom.

My invention resides further in apparatus of the character referred to wherein separate portions or units of the heat transfer structure, as separate groups of condenser tubes, are subjected to independent streams of cooling medium.

My invention resides further in apparatus of the character referred to wherein means are provided for automatically controlling the independent streams of cooling medium and proportioning said streams relatively to each other.

My invention resides in the features of construction and combination hereinafter described and claimed.

For an illustration of one of the forms my invention may take, reference is to be had to the accompanying drawings, in which:

Fig. 1 is a vertical sectional view, partly in elevation, of apparatus embodying my invention.

Fig. 2 is an elevational view of the apparatus illustrated in Fig. 1, in combination with a main or large condenser.

Referring to Fig. 1, E is an ejector of any

suitable type, here indicated as of the tubular type, whose suction port, a, communicates with the main condenser or other vessel or region from which elastic fluid is to be withdrawn and compressed. Elastic motive fluid, as steam, is supplied to the nozzle structure of the ejector E, through pipe b, controlled by valve C. The diffuser d of ejector E delivers into the condensing apparatus M. Condensing apparatus M comprises two units A and B. Upper unit A comprises upper and lower tube plates g and h supporting the condenser tubes k. Supported between the tube plates g and h and surrounding tubes k is the cooling water jacket or shell L having cooling water inlet m and cooling water outlet n, both communicating with shell L adjacent the upper tube plate g. Extending downwardly from tube plate g within shell L is a baffle plate i, terminating short of tube plate h and dividing the cooling water chamber formed by tube plates g and h and shells L into two compartments q and r. Communicating with the ends of condenser tubes k, above tube plate g, is a chamber C divided into compartments c and f by a partition p. Compartment e receives the discharge from ejector E and communicates with the condenser tubes k in chamber r of the cooling water jacket. The chamber f communicates with the condenser tubes k in chamber q of the cooling water jacket, and through conduit K with a second ejector E¹.

Condenser unit B is similar to unit A having upper and lower tube plates g¹ and h¹, condenser tubes k¹, cooling water jacket or shell L¹, cooling water inlet and outlet m¹ and n¹, and baffle i¹ dividing the cooling water jacket into two chambers q¹ and r¹.

On the lower end of condenser unit A, secured to lower tube plate h, is a shell o divided into two chambers or conduits s and t communicating, respectively, with the condenser tubes k in chamber q and the condenser tubes k in chamber r of the cooling water jacket or shell L. The upper end of condenser unit B is provided with a shell o¹ having two conduits s¹ and t¹ communicating, respectively, with conduits s and t and with condenser tubes k¹ in chambers q¹ and r¹ of cooling water jacket L¹.

On the lower end of condenser unit B is

a chamber C^1 , communicating with condenser tubes k^1 and with the condensate conduit j , the latter controlled by valve v .

Referring to Fig. 2, the intake a of ejector E communicates through pipe u , controlled by valve x , with the large surface condenser D having inlet w for fluids to be condensed and a condensate discharge pipe N . Cooling water is supplied to condenser D through pipe y by means of pump F , operated by motor G , and discharges from the condenser through pipe z . Communicating with pipe y , intermediate pump F and condenser D , is a cooling water pipe y^1 , controlled by hand valve w^1 and thermostatic valve V and discharging into cooling water intake m^1 of condenser unit B . The cooling water outlet n^1 of condenser unit B connects through pipe z^1 with pipe z .

Condensate discharge conduit N from condenser D discharges into the intake of pump H , operated if desired or convenient, by motor G . Pump H discharges through pipe N^1 into the cooling water intake m of condenser unit A , the cooling water outlet n discharging to waste, or preferably to the boiler feed water tank.

The condensate discharge conduit j connected with the bottom of condenser unit B leads to the intake of pump H through a vacuum trap I and pipe N .

Thermostatic valve V is controlled by thermostat T subjected to the cooling water in chamber r of condenser unit A .

The operation is as follows:

Waste steam mixed with uncondensable gas, as air, from any source, as a steam engine, is discharged into condenser D where the steam is condensed by contact with heat transfer structure cooled by cooling water supplied by pump G through pipe y and leaving the condenser through pipe z . The uncondensed fluid from condenser D passes through pipe u to the intake a of ejector E , wherein it is ejected by motive fluid, as steam, supplied through pipe b , and discharges through diffuser d into compartment e of chamber C on condenser unit A . From compartment e the mixture of uncondensed fluid and motive fluid passes through condenser tubes k in chamber r downwardly through conduit t of shell o and conduit t^1 of shell o^1 into condenser tubes k^1 of chamber r^1 . Leaving the latter tubes k^1 , the gases pass through chamber C^1 and upwardly through condenser tubes k^1 in chamber q^1 , on through conduits s^1 and s in shells o^1 and o into condenser tubes k in chamber q from which they discharge through compartment f and conduit K to the intake of pump or ejector E^1 .

Condenser tubes k in condenser unit A are cooled by condensate leaving the condenser D through pipe N , said condensate passing

from pipe N through pump H , pipe N^1 and through chambers q and r , respectively, to waste. Condensate from both condenser units A and B collecting in chamber C^1 flows through pipe j and trap I into pipe N , from which it also is passed through chambers q and r of condenser unit A . All of the condensate is thus employed as cooling medium for condenser unit A . While I have here shown the use of condensate as cooling medium for unit A , it is to be understood that my invention is not limited thereto, and cooling medium from any other source may be employed.

Cooling medium, as water, is supplied to condenser unit B from the discharge of pump F passing through pipe y^1 , chambers q^1 and r^1 , respectively, of condenser unit B , and discharging through pipe z^1 into pipe z .

In order to save cooling water or use as little thereof as possible, the cooling medium, as condensate water, supplied to condenser unit A is utilized to its fullest extent and only sufficient cooling water is supplied to condenser unit B to complete the condensation. For this purpose thermostatic valve V and thermostat T are adjusted to supply the requisite quantity of cooling water to condenser unit B . If the amount of heat to be absorbed by the cooling medium in condenser unit A decreases, or the supply of condensate water employed as cooling medium increases or its temperature decreases, the thermostat T and valve V operate to reduce the supply of cooling water to condenser unit B . If, on the contrary, the temperature of the cooling medium in condenser unit A increases, then thermostat T and valve V operate to increase the supply of cooling water to condenser unit B . Thus, the supply of cooling water is always sufficient, but not in excess of that necessary to accomplish complete or any desired predetermined degree of condensation.

What I claim is:

1. The combination with an ejector, of condenser structure into which said ejector discharges comprising a plurality of condenser units, and means for subjecting said units respectively to different cooling media.

2. The combination with an ejector, of condenser structure into which said ejector discharges comprising a plurality of condenser units, a group of tubes in each condenser unit, said groups of tubes of the different units being serially connected and conducting the discharge from said ejector, and means for subjecting said groups of tubes to different streams of cooling fluid.

3. The combination with an ejector, of condenser structure into which said ejector discharges comprising a plurality of condenser units, sources of cooling media of different temperatures, and means conducting

one of said media to one of said units and another of said media to another of said units.

4. The combination with an ejector, of condenser structure into which said ejector discharges comprising a plurality of condenser units, sources of cooling media of different temperatures, and means conducting one of said media to one of said units and another of said media to another of said units, the ejector discharge coming first into heat transfer relation with the cooling medium of higher temperature.

5. The combination with an ejector, of condenser structure into which said ejector discharges comprising a plurality of condenser units, means for subjecting said units respectively to different streams of cooling medium, and a second ejector connected in series with said first named ejector through said condenser units.

6. The combination with an ejector, of condenser structure into which said ejector discharges comprising a plurality of groups of tubes disposed at different altitudes and serially conducting the discharge from said condenser, and means for subjecting said groups of tubes to cooling fluid, a lower group of tubes conducting downwardly the condensate formed in an upper group of tubes.

7. The combination with an ejector, of condenser structure into which said ejector discharges comprising a plurality of condenser units, means for conducting cooling water through one of said units, and means for conducting condensate from one of said units through the cooling medium passage of another of said units.

8. The combination with an ejector, of condenser structure into which said ejector discharges comprising a plurality of condenser units, groups of tubes in each of said units conducting the ejector discharge, means for passing different cooling media in contact with the different tube groups, and a second ejector connected in series with said first named ejector through said condenser structure.

9. The combination with an ejector, of condenser structure into which said ejector discharges comprising a plurality of condenser units, means for subjecting said units, respectively, to different cooling media of different temperatures, and a second ejector connected in series with said first named ejector through said condenser structure.

10. The combination with an ejector, of condenser structure into which said ejector discharges comprising a plurality of condenser units, means for subjecting said units, respectively, to different cooling media of different temperatures, the ejector discharge coming first into heat transfer relation with the cooling medium of higher

temperature, and a second ejector connected in series with said first named ejector through said condenser structure.

11. The combination with an ejector, of condenser structure into which said ejector discharges comprising a plurality of condenser units, tubes in each of said units conducting the ejector discharge in series, means connecting the tubes of the different units in series, and means conducting cooling medium into and from each of said units.

12. The combination with an ejector, of condenser structure into which said ejector discharges comprising a plurality of condenser units, tubes disposed in the different units and conducting the ejector discharge in series, and means conducting cooling medium into and from each of said units, each of said units having a baffle around which the cooling medium passes.

13. The combination with an ejector, of condenser structure into which said ejector discharges comprising communicating structurally condenser units, tubes disposed in the different units and conducting the ejector discharge in series, means conducting cooling medium into and from each of said units, each of said units having a partition around which the cooling medium passes, and a second ejector receiving the discharge from said first ejector through said condenser structure.

14. The combination with a main condenser, of ejector structure withdrawing uncondensed fluid therefrom, a second condenser into which said ejector structure discharges comprising a plurality of condenser units, means for delivering to one of said units a single cooling medium consisting of condensate from said main condenser, and means for delivering different cooling medium to another of said units.

15. The combination with a main condenser, of means for supplying cooling medium thereto, an ejector withdrawing uncondensed fluid from said main condenser, condenser structure into which said ejector discharges comprising a plurality of condenser units, independent cooling medium passes for said units, a second ejector serially connected with said first named ejector through said condenser structure, means for delivering only condensate from said main condenser to one of said passes, and means for delivering different cooling medium to another of said passes.

16. The combination with a main condenser, of ejector structure withdrawing uncondensed fluid therefrom, condenser structure into which said ejector structure discharges comprising a plurality of condenser units, independent cooling water passes for said units, means for delivering only cooling medium of said main condenser to one

of said passes, and means for delivering only condensate from said main condenser to another of said passes.

17. The combination with a main condenser, of means supplying cooling medium thereto, ejector structure withdrawing uncondensed fluid from said condenser, condenser structure into which said ejector structure discharges comprising a plurality of condenser units, independent cooling water passes for said units, means delivering only cooling medium of said main condenser to one of said passes, and means delivering only condensate from said main condenser to another of said passes, the discharge from said ejector structure coming first into heat transfer relation with the condensate from said main condenser.

18. The combination with an ejector, of condenser structure into which said ejector discharges comprising two condenser units, two groups of tubes in each unit, each of said groups of tubes in one of said units being serially connected with one of said groups of tubes in the second of said units and the groups of tubes of said second unit being serially connected, and means for conducting independent streams of cooling water through said condenser units.

19. The combination with an ejector, of condenser structure into which said ejector discharges comprising two condenser units, two groups of tubes in each unit, each of said groups of tubes in one of said units being serially connected with one of said groups of tubes in the second of said units and the groups of tubes of said second unit being serially connected, means for conducting independent streams of cooling water through said condenser units, and a second ejector serially connected with said first ejector through said groups of tubes.

20. The combination with an ejector, of condenser structure receiving the discharge from said ejector comprising condenser units, condenser tubes in each of said units, cooling medium passes in each of said units, means for passing condensate from one of said units through the cooling medium pass of another of said units, means for passing cooling medium through the cooling medium pass of said one unit, and a second ejector serially connected with said first named ejector through said condenser structure.

21. The combination with an ejector, of a condenser structure receiving the discharge from said ejector comprising condenser units, condenser tubes in each of said units, means for supplying cooling medium to each of said units, and means responsive to the temperature of the cooling medium in one of said units controlling the supply of cooling medium to another of said units.

22. The combination with ejectors, of condenser structure comprising a condenser

unit, groups of tubes in said unit, a chamber having compartments communicating with each of said groups of tubes, one of said compartments communicating with the discharge of one of said ejectors and another of said compartments communicating with the suction of a second of said ejectors, a second condenser unit, serially connected groups of tubes in said second condenser unit, said groups of tubes in said first named condenser unit being serially connected through said groups of tubes in said second condenser unit, and means for passing cooling medium from separate sources through said condenser units.

23. The combination with ejectors, of condenser structure comprising an upper and a lower condenser unit, a chamber on the upper end of said upper unit, a partition dividing said chamber into two compartments, one of said compartments communicating with the discharge of one of said ejectors, the other of said chambers communicating with the suction of another of said ejectors, groups of condenser tubes in said upper unit communicating with said compartments, groups of condenser tubes in said lower unit, a chamber on the lower end of said lower unit connecting said groups of condenser tubes in said lower unit serially, conduits on the adjacent ends of said condenser units connecting each of said groups of tubes in said upper unit with one of said groups of tubes in said lower unit, a cooling medium pass for each of said units, and means for passing independent streams of cooling medium through the cooling medium passes of said units.

24. The combination with a main condenser, of means for supplying cooling medium thereto, of an ejector withdrawing uncondensed fluid from said main condenser, condenser structure receiving the discharge from said ejector comprising condenser units, groups of tubes in each of said units serially connected, a second ejector serially connected with said first named ejector through said groups of tubes of said units, cooling medium passes for said condenser units, and means for delivering condensate from said main condenser to one of said passes.

25. The combination with an ejector, of a condenser receiving the discharge thereof comprising a plurality of condenser units, means for supplying cooling medium to each of said units, and means controlled by the cooling medium of one of said units controlling the supply of cooling medium to another of said units.

26. The combination with an ejector, of a condenser receiving the discharge thereof comprising a plurality of condenser units, means for supplying cooling medium to each of said units, and means responsive to

a condition of the cooling medium of one of said units controlling the supply of cooling medium to another of said units.

27. The combination with an ejector, of a condenser receiving the discharge thereof comprising a plurality of condenser units, means for supplying independent streams of cooling medium of different temperatures to said units, and means responsive to the 10 temperature of a stream of cooling medium of higher temperature controlling a stream of cooling medium of lower temperature.

28. The combination with an ejector, of condenser structure receiving the discharge 15 thereof comprising a plurality of condenser units, means for supplying cooling medium to each of said units, a valve controlling the supply of cooling medium to one of said units, and a thermostat subjected to the cooling medium of another of said units controlling said valve.

29. The combination with an ejector, of condenser structure receiving the discharge thereof comprising a plurality of condenser units, an independent cooling medium pass for each of said units, means for conducting independent streams of cooling medium of different temperatures through said passes, the discharge of said ejector coming first 30 into heat transfer relation with the cooling medium of higher temperature, a valve controlling a stream of cooling medium of lower temperature, and a thermostat subjected to said cooling medium of higher temperature 35 controlling operation of said valve.

30. The combination with an ejector, of condenser structure receiving the discharge thereof, said condenser structure having a plurality of independent cooling medium 40 passes, and means responsive to the temperature of the cooling medium in one of said passes controlling the amount of cooling medium in another of said passes.

31. The combination with an ejector, of condenser structure receiving the discharge therefrom, means for delivering a plurality of cooling media to said condenser structure, and means responsive to a condition of one of said cooling media controlling another of said cooling media.

32. The combination with an ejector, of condenser structure receiving the discharge therefrom, means for delivering a plurality of cooling media to said condenser structure, and means responsive to changes in temperature of one of said cooling media controlling the supply of another of said cooling media.

33. The combination with a main condenser, of ejector structure for withdrawing fluid therefrom, a second condenser receiving the discharge from said ejector, means for conducting condensate from said main condenser to said second condenser to operate as a cooling medium therein, means for supplying a second cooling medium to

said second condenser, and means responsive to changes in the temperature of said condensate controlling the rate of supply of said second cooling medium.

34. The combination with an ejector, of condenser structure into which said ejector discharges comprising a plurality of groups of tubes disposed at different altitudes and serially conducting the discharge from said condenser, means for subjecting said groups of tubes to cooling fluid, a lower group of tubes conducting downwardly the condensate formed in an upper group of tubes, and a condensate draw-off common to said groups of tubes. 75

35. The combination with an ejector, of condenser structure into which said ejector discharges comprising a plurality of groups of tubes disposed at different altitudes and serially conducting the discharge from said condenser, means for subjecting said groups of tubes to cooling fluid, a lower group of tubes conducting downwardly the condensate formed in an upper group of tubes, 80 means for cooling one of said groups of tubes with a cooling medium, and means for cooling another of said groups of tubes with another cooling medium. 85

36. The combination with an ejector, of condenser structure into which said ejector discharges, said condenser structure comprising a plurality of surface condenser units disposed, respectively, in different shells, and means for passing different cooling media through the different condenser 90 unit shells, respectively. 95

37. The combination with an ejector, of condenser structure into which said ejector discharges, said condenser structure comprising a plurality of surface condenser units disposed, respectively, in different shells, 105 and means for passing different cooling media through the different condenser unit shells, respectively, in directions counter to the directions of passage of the ejector discharge. 110

38. The combination with an ejector, of condenser structure into which ejector discharges, said condenser structure comprising a plurality of surface condenser units disposed, respectively, in different shells, each shell containing a plurality of portions of the passage for the ejector discharge, the portions of said passage in one of said condenser units communicating directly one with the other and connecting the different portions of the discharge passage in another of said units, and means for passing different cooling media through the different condenser units. 115 120 125

In testimony whereof I have hereunto affixed my signature this 6th day of May, 1920.

ROBERT SUCZEK.
